FINISHING APPARATUS FOR MOLDED
PULP PAPER ITEMS

Kenneth L. Crabtree, Fairfield, Maine, and Donald E. Burt, Ipswich, Mass., assignors to Keyes Fibre Company, Inc., Waterville, Maine, a corporation of Maine
Filed Aug. 7, 1962, Ser. No. 215,368
21 Claims. (Cl. 162—415)

This invention relates to a method and apparatus for after finishing molded pulp paper articles and, in particular, relates to improvements in methods and apparatus for after finishing molded pulp paper items to produce a quality finish on such articles.

Molded pulp paper articles manufactured by current techniques are, for many uses, perfectly satisfactory in the form in which conventional equipment produces them. However, where printing operations are required, a better finish than has been available before is necessary. Also where it is desired to produce a better quality article, after finishing is often required. After finishing involves taking the already molded and dried paper articles, subjecting them to severe conditions of heat, temperature and sometimes moisture to permanently form them, and correcting any warping or imperfections which have resulted from the normal molding and drying operations. After finishing methods and apparatus have been used previously but are not entirely satisfactory, since they are slow in operation and often unreliable. In order for methods and apparatus to be successfully used in connection with a production line for molded pulp paper items, it is necessary that there be a maximum of speed and reliability in the handling of such items. This results from the fact that the normal molding and drying process produces articles at a fairly rapid, continuous rate and, any equipment which is to form a portion of the production line must be capable of trouble-free operation in order to avoid having to stop the entire production line, with the consequent loss of production time.

The device of the present invention is designed as an improvement over the methods and apparatus described in the Randall Patents 2,704,493 and 2,752,830. The Randall patents describe a device in which molded pulp paper articles are after finished in an intermittent operation requiring that the articles come to a halt during the after finishing operation. This intermittent operation is undesirable, since the remaining equipment in the production line operates at a continuous rate and the necessary stoppage results in slowing down the entire production line.

It is therefore the object of this invention to provide an improvement in methods and apparatus for after finishing molded pulp paper articles which is continuous in operation and is more reliable than previously available devices.

The methods and apparatus of this invention are described as forming a portion of the production line for molded pulp paper articles. While the device is suitable, with slight modifications for handling any type of molded pulp paper item, it will be described in connection with the production of molded pulp paper egg cartons.

Previously molded and partially or completely dried egg cartons are delivered from the drying oven conveyors now used. An extension conveyor may be provided at the end of the drying oven conveyor, if necessary, in order to conduct the egg cartons to the device of this invention. One or more finishing devices, as described hereinbelow, may be used in order to handle the output of pulp forming equipment, depending upon the output of such forming equipment.

The device as illustrated may, through replacement of parts and adjustment of other elements, handle the

2

output of a molding machine producing either 2 by 6 or 3 by 4 egg cartons at very high rates of production. For ease of understanding the method of this invention, the steps will be discussed in the order they appear to an egg carton passing through the device of this invention. The conveyor extension, as indicated above, carries the cartons in parallel rows, normally six abreast in the embodiment illustrated, to the infeed conveyor. The infeed conveyor is designed to properly time the approaching rows of egg cartons as they enter into the cross-feed conveyor. Additionally, the infeed conveyor provides a means for by-passing the remaining elements in the device in the event of mechanical failure in the remaining mechanisms. The infeed conveyor, accordingly, consists of two major assemblies. A dumping conveyor, having six belts which are of the same size and operate at the same speed as the belts of the extension conveyor, is provided. Between the belts are two narrow belts driven by the same shafts which are vibrated to cause the egg cartons to be properly aligned as they pass along on the carrier belts. The dumping conveyor is pivotally attached to a frame so that by manually operating an air motor the dumping conveyor can be tilted to drop the egg carton on a dumping discharge conveyor thus by-passing the remainder of the system.

The second portion of the infeed conveyor is a timing and aligning conveyor. This conveyor consists of a smooth platform divided into six parallel channels into which the egg cartons are delivered by the dumping conveyor. Two separate pusher chain systems are provided as part of the timing and aligning conveyor to engage the egg cartons and move them at a rate sufficient to insure their arrival in position over the cross-feed conveyor six at a time. The timing and aligning conveyor is synchronized with and driven by the same means as the cross-feed conveyor, thereby insuring a continuous flow of egg cartons to the cross-feed conveyor. The timing and aligning conveyor pushes the egg cartons over, for they are lying in the flat condition in which they came out of the dry oven, on their edge so that they are positioned vertically and are properly arranged to be carried continuously to the rotary after press.

The cross-feed conveyor is made up of handle chains which have pusher elements connected thereto. Pusher elements are mechanically and electrically operated so that six at a time enter behind the respective six cartons delivered by the timing and aligning conveyor and carry the cartons in a vertical condition to the rotary after press. Means are provided at the forward end of the cross-feed conveyor for retracting each of the pushers once the egg cartons have been delivered to the rotary after press. The pushers remain in the retracted position during their return along the back of the cross-feed conveyor until they again arrive at the position directly beneath the timing and aligning conveyor, at which time six are tripped, causing the pushers to be extended and engage the next six cartons. Thus the cross-feed conveyor provides a continuous flow of cartons to the rotary after press.

As the cartons pass beyond the tangent point of the rotary after press, pick-up rods associated to the dies on the rotary after press engage the cartons and direct them along a curved rail. The curved rail's bottom edge ends and the cartons drop by gravity assisted by a camming rail into dies to come to rest against a carton positioning ledge. The carton positioning ledge contains safety elements which prevent the dies from closing in the event no carton is present within the die.

The rotary after press is driven at a constant rate of speed synchronized to the speed of movement of the cartons on the cross-feed conveyor. Cams operate electric and hydraulic devices which successively cause low

hydraulic pressure to be introduced to the piston connected to the inner die, causing the inner die to move toward the outer die which causes the creasing bars to close against the egg cartons as the rotation of the rotary after press continues. Further motion of the inner die toward the outer die causes the carton positioning ledge to be retracted once the carton is held in place by the creasing bars. Continued application of low pressure hydraulic fluid to the piston closes the inner die against the outer die. At the end of the stroke, high pressure hydraulic fluid is introduced into the piston to exert the required smoothing force on the carton. The dies are electrically heated under thermostatic control and may also be provided with steam if necessary. The egg cartons, as they continue to be carried around by the rotary after press, are therefore subjected to severe conditions of heat and pressure and may also be subjected to moisture treatment. Just before the egg cartons arrive at a position corresponding to the cross-feed conveyor, a cam causes the inner and outer dies to separate whereupon the creasing bars lift the carton away from each die with the assistance of air pressure through the face of either or both dies if necessary. Final movement of the inner die causes the creasing bars to be separated enough to allow the carton to drop on a discharge conveyor positioned beneath the rotary after press. A separate cam causes the carton positioning ledge to be returned to the horizontal position. The cycle repeats itself continuously.

Further features and advantages of the method and apparatus of this invention will become more apparent when taken in connection with the detailed descriptions below along with the drawings in which:

FIG. 1 is an elevation view of a device constructed in accordance with the teachings of this invention;

FIG. 2 is a plan view of the device illustrated in FIG. 1;

FIG. 3 is a plan view of the infeed conveyor portion of the device illustrated in FIG. 1;

FIG. 4 is a side elevation view of the conveyor of FIG. 3;

FIG. 5 is a side elevation view of the timing and aligning lug conveyor portion of the conveyor of FIGS. 3 and 4;

FIG. 6 is a front view taken on the line 6—6 of FIG. 5;

FIG. 7 is a partial plan view of the cross-feed conveyor;

FIG. 8 is a front elevation view of the conveyor of FIG. 7;

FIG. 9 is a side elevation view of the conveyor of FIG. 7;

FIG. 10 is a plan view of the pusher assembly part of the conveyor of FIG. 7;

FIG. 11 is a front elevation view of the cross feed conveyor adapted for use with three by four egg cartons;

FIG. 12 is an enlarged partially cutaway view of a portion of the conveyor shown in FIG. 11;

FIG. 13 is a partial plan view of the conveyor of FIG. 11;

FIG. 14 is a plan view of the turret and the associated mechanical drive;

FIG. 15 is a front elevation view of the carton diverting mechanism associated with the cross feed conveyor;

FIG. 16 is a plan view of the diverting mechanism of FIG. 15 and associated portions of the machine of this invention;

FIG. 17 is a longitudinal cross section of the base of the turret;

FIG. 17A is a plan view of the air ejection plate in FIG. 17;

FIG. 18 is a bottom view of one set of dies in open position;

FIG. 19 is a side view of the dies shown in FIG. 18;

FIG. 20 is a plan view of the outer stationary die;

FIG. 21 is a face view of the die shown in FIG. 20;

FIG. 22 is a partial cutaway view of the die shown in FIG. 21;

FIG. 23 is a close-up side view of the platform and latching mechanism shown in FIGS. 21 and 22;

FIG. 24 indicates the latched and unlatched condition for the platform of FIG. 23;

FIG. 25 indicates a typical cam and switch mechanism;

FIG. 26 is a plan view of certain cam arrangements on the stationary frame;

FIG. 27 is an elevation view of cam arrangements on the stationary frame;

FIG. 28 is an electrical schematic of the die control circuits;

FIG. 29 is an electrical schematic of the electrical controls for the device of FIG. 1;

FIG. 30 is a mechanical schematic of the hydraulic system showing the arrangement when a die is opening;

FIG. 31 is identical with FIG. 30 except that it shows the arrangement when a die is closing by the low pressure system; and

FIG. 32 is identical with FIG. 31 except that it shows the hydraulic arrangement during after pressing when high pressure is applied to the dies.

Referring now to the figures, the device illustrated in FIGS. 1 and 2 shows one complete machine and a portion of the conveyor system for a second machine. Since the operation of both machines would be the same it is unnecessary to describe both.

It may be necessary or advisable, because of space limitations to operate the second system in a direction which would mean that the cross-feed conveyor and the direction of rotation of the rotary after press be opposite to that described in connection with the machine illustrated.

Referring now to FIGS. 1 and 2, it will be seen that the major portions of the system are identified as follows:

The extension conveyors 30, 31 pick up egg cartons from the drying oven conveyors (not shown) by means of belts 32. In the case of the lower extension conveyor 31, it discharges onto an incline conveyor 34 which forms a portion of the extension conveyor leading to a second machine which is not illustrated.

The upper extension conveyor 30 consists of six separate belts 32 carried on common shafts 35, 36. The drive shaft 35 for the belts 32 is driven by the drying oven conveyor preferably at the same surface speed as the drying oven conveyor. The belts 32 are spaced to receive six rows of egg cartons 37 as they leave the drying oven.

The conveyor extension 30 will therefore transport the egg cartons 37, spaced in six columns, to the infeed conveyor 38 section of the device of this invention.

As briefly indicated above, the infeed conveyor 38 has two functions. Its primary function is to properly time the egg cartons 37 so that they will enter the cross-feed conveyor 39 at the proper time, six abreast. Secondarily, the infeed conveyor 38 must provide a means for bypassing the cross-feed conveyor 39 (which carries the cartons 37 to the rotary after press indicated generally at 40). In order to accomplish these purposes, the infeed conveyor 38 consists of two major assemblies, the dumping conveyor 41 and the timing and aligning conveyor 42 (which are shown in greater detail in FIGS. 3, 4, 5 and 6).

The dumping conveyor 41 has six belts 43 which are of the same width and spacing as the belts 32 of the extension conveyor 30. The belts 43 abut in an end to end relationship with belts 32. In addition to belts 43, narrow belts 44 are provided between each of belts 43. Belts 43, 44 are all driven by the same shafts. Between the drive shaft 45 and the idler shaft 46 for belts 43, 44 there is provided a third shaft 47. Between shafts 46 and 47 is vibratory shaft 47a which contains elements

which vibrate the narrow belts 44 sufficiently to insure that the cartons 37 are properly aligned as they are carried along by carrier belts 43. The driving shaft 45 for the belts 43 is in turn driven by the idler shaft 36 of conveyor extension 30 so that the egg cartons 37 move at the same rate of speed on dumping conveyor 41 as they move on conveyor extension 30.

Shaft 47a also serves as a pivot for frame 48 of the dumping conveyor 41. As may be seen in FIG. 4, dumping conveyor frame 48, in normal operation, lies horizontal. If however, it is desired to by-pass the remainder of the machine, frame 48 is tilted by operating the air motor 49, which motor 49 is controlled from the operator control panel by the operator. It might be desired to by-pass the remainder of the system in this fashion when some other portion of the system is not properly operating.

Rotation of the air motor drive 49 causes rotation of worm wheel 50 through worm 50a which, through arms 51 and 52, forces the end of the frame 48, to which arm 52 is pivotally attached, upward to the position indicated by dotted lines in FIG. 4. The cartons 37 would then be carried up on belts 43 down the now inclined surface of the belts 43 between shafts 45 and 46 and be dropped on dump discharge conveyor 53. The dump discharge conveyor 53 carries the cartons away to another portion of the plant.

Under normal operation the frame 48 remains horizontal and the belts 43 carry the cartons 37 into the timing and aligning section 42 of the infeed conveyor 38.

The frame of the timing and aligning conveyor 42 is a stationary platform 54 which is divided into six troughs 55. Pointed dividers 56 separate the troughs 55. These dividers 56 are so pointed and arranged (see FIGS. 2 and 3) as to channel the cartons 37 into the troughs 55 so that the major axis of the cartons 37 will lie parallel with the major axis of the troughs 55. In this fashion, the cartons are transferred to and properly arranged on the spacing conveyor 42 portion of the infeed conveyor 38 as they come off the pumping conveyor 41 portion.

Two separate lug conveyors 57, 58 are mounted in the spacing and aligning conveyor 42 frame above the platform 54 and the troughs 55. These lug conveyors 57, 58 space apart and align the cartons 37 in the troughs 55 so that the cartons 37 are properly fed to the cross-feed conveyor 39.

The first conveyor 57 is a timing lug conveyor. This timing lug conveyor 57 is a series of single chains 59, extending from shaft 57a to shaft 57b, each of which runs parallel to a separate one of the troughs 55. On each chain 59, there is mounted a single T-shaped bar to which is attached two flexible pick-up lugs 60. As the cartons are carried to the end of the dumping conveyor 41, they come to rest in the troughs 55. At that point, the pick-up lugs 60 make friction contact with the cartons 37 anywhere along the surface of the carton, one lug 60 contacting the cover and the other lug contacting the pocketed portion of the carton 37. In this manner the lugs 60 drive the carton 37 along the troughs 55 into position for the second or aligning lug conveyor 58.

To avoid back-up on the dumping conveyor 41, the speed of the pick-up lugs 60 is greater than the speed of the dumping conveyor 41, belts 43.

The aligning lug conveyor 58 is composed of a series of paired parallel chains 61 extending from the shaft 58a to the shaft 58b, each pair running parallel to a separate one of the troughs 55. At the same longitudinal position in each chain 61, a single flexible lug 62 is provided. The chains 61 run parallel to the surface of the troughs 55 and are at the same height above the surface of the troughs 55 as are the chains of the timing lug conveyor 57. The lugs 62 on this aligning lug conveyor 58 are so spaced and the speed of the conveyor 58 is so timed that the lugs 62 engage the rear

5

edge of the egg cartons 37 in the position at which the egg cartons 37 have been placed by the timing lug conveyor 57. The lugs 62 then drive the cartons 37, six at a time, out of the trough 55 into the cross-feed conveyor 39, where the cartons 37 come to rest.

The aligning lug conveyor 58 runs faster than the timing lug conveyor 57 which, in turn, runs faster than the dumping conveyor 41. The successive increase in conveyor speeds assures that the cartons 37 will not back up, which back-up would push the forward carton ahead to a point where the lugs 62 on the aligning conveyor 58 might not engage the cartons 37 at their rear edge. The speed arrangement also allows any out-of-line cartons 37 in the troughs 55 to be brought into alignment during their passage through troughs 55.

Both conveyors 57 and 58 are driven from the cross-feed conveyor 39 drive as will be described in detail later. The lugs 49, 62 are thereby synchronized with the cross-feed conveyor 39 to place a row of six cartons 37 in the cross-feed conveyor 39 at the proper time in the after press 40 cycle. In normal operation there will often occur a condition in which less than six cartons will be fed to the cross-feed conveyor. It is for this reason that many of the safety features described below are provided in the rotary after press 40.

The function of the cross-feed conveyor 39 is to combine the six rows of single cartons 37 into a single transverse row and properly time the entrance of the cartons 37 into the rotary after press 40. It should be noted that the cartons on conveyors 30, 41 and 42 were all lying flat in the condition that they were received from the drying oven 33. The second lug conveyor 58, in forcing the cartons out of troughs 55, positions the cartons 37 on their end so that they came to rest on cross-feed conveyor 39 in a vertical position. FIG. 7 shows cartons 37 flat in troughs 55 just before being up-ended. FIG. 8 shows cartons 37 after being up-ended by being pushed over into the cross-feed conveyor 39 and out of the troughs 55 by lugs 62. FIG. 9 is an end view which shows the relation between the plane of the troughs 55 and the plane of the cross-feed conveyor 39. FIG. 9 shows that gravity feed assists the lugs 62 in transferring cartons 37 from the troughs 55 to the conveyor 39.

In view of the purpose of maintaining maximum flexibility with a minimum of change of parts, separate operations are performed on 2 by 6 and 3 by 4 egg cartons during their passage across cross-feed conveyor 39. 2 by 6 cartons remain on their ends in a vertical plane, whereas 3 by 4 cartons are rotated so that they are turned on their sides, while remaining in a vertical plane, before reaching the rotary after press 40. Each of these different types of cross-feed conveyors 39 will be described.

The cross-feed conveyor 39 (see FIG. 7) includes a constantly moving chain 64 which carries retractable pusher assemblies 65. In addition, a pusher timing and tripping mechanism must be provided. The pusher assemblies 65 are carried in a normally retracted position and are tripped in groups of six when they are properly positioned with respect to the cartons 37.

When cartons 37 (normally six in number) are up-ended in front of the cross-feed conveyor 39, pusher assemblies 65 pass behind the cartons 37 without making contact with the cartons 37 until one of a series of periodic signals is received which unlatches the pusher arm 66 on each assembly 65. The assemblies 65 are so spaced that the unlatching causes six pusher arms 66 to simultaneously engage the six cartons 37. The cartons are then pushed to the left as seen in FIGS. 7 and 8 by the arms 66 as the chain 64 rotates.

As shown in FIG. 7, on the left, there is a cam 67 which is mounted coaxially with a driven spur gear 68, which gear 68 in turn engages a driving spur gear 69. The driving spur gear 69 is mounted on the vertical

drive shaft 70 (see FIG. 8) which delivers power to the cross-feed conveyor 39 and, as will be pointed out later, to the first and second lug conveyors 57 and 58. The size of the gears 68, 69 are selected so that a lobe on cam 67 engages a limit switch 72 once for every six cartons 37 that are finished by the rotating turret after press 40. The limit switch 72 is electrically connected to a solenoid 73 which causes a pin 74 to rotate upon being energized by the closing of the limit switch 72. The pin 74 carries six tripping fingers 75 which fingers 75, when rotated, intercept the latching arms 76 of the pusher assemblies 65. Upon intercepting the latching arm 76, the pusher arm 66 is released and placed in position to engage carton 37. (The relationship of the latching arm 76 to the pusher arm 66 is best seen in FIG. 10.)

A pusher arm 66 then moves an egg carton along the cross-feed conveyor 39 guides until the egg carton 37 is adjacent to the rotary after press 40. When each carton 37 passes the center line of rotary after press 40, a vertical pick-up rod 77 on the rotary after press 40 will engage the carton 37 in the V-shaped area between top and bottom portions of the carton. The pick-up rod 77 carries the carton 37 along a curved track 78 away from the pusher arm 66 leading to rotary after press 40.

The pusher assembly 65 continues its travel (attached as it is to chain 64) and at about the same time as the pick-up rod 77 engages the carton 37, the pusher arm 66 is retracted by the operation of stationary cam 80 which acts on a roller 81 located at the rear end of pusher arm 66. Since a new group of pusher assemblies 65 is already in position behind cartons 37, coming from the timing and aligning section 42 of the infeed conveyor 38, the operations just described will be repeated on a new group of six cartons 37. Thus, a continuous line of cartons will be presented to the rotary after press 40.

The cross-feed conveyor 39 receives power from a vertical drive shaft 70 (see FIG. 8). The shaft 70 is topped by a driving sprocket gear 90 (see FIG. 7) which engages the cross-feed conveyor chain 64. A driven sprocket gear 91 (see FIG. 8) is driven by the chain 64. The driven sprocket gear 91 supplies power to the timing lug conveyor 57 and to the aligning lug conveyor 58 through a reducing unit 92 which also serves to rotate by 90° the plane of delivery power. A shaft runs horizontally from the reducing unit 92 to deliver power to a driving pulley 94 (see FIG. 9). A belt 95 is driven by the pulley 94 to in turn drive driven pulley 96. Sprocket wheels mounted on the axis of driven pulley 96 engages the chains 59 and 61 thereby providing motive power to the timing lug conveyor 57 and the aligning lug conveyor 58.

FIGS. 11, 12 and 13 illustrate an adaptation of the cross-feed conveyor 39 for use with 3 by 4 egg cartons 37A. The operation is essentially the same as described above except that the cartons 37A must be turned sideways during their passage along cross-feed conveyor 39 so that they can be engaged by the pick-up rods 77. The cartons 37A are rotated by a rotating wheel 85 which has spokes 86 attached thereto. Wheel 85 is driven by a gear 82 mounted on the shaft of wheel 85, which is in turn driven by spur gear 91 through gears 83 and 84. Spur gear 83 is mounted coaxially with the driven sprocket gear 91 which gear 91 receives power through the chain 64 as described in connection with the 2 by 6 carton arrangement. The reducing unit 92 is run off the shaft of the wheel 85 through belt 87 rather than off the shaft of the gear 91.

As the cartons 37A are carried along by the pusher arms 66, their rearmost edge is engaged by one of the spokes 86 and the cartons are turned counterclockwise as seen in FIG. 11. This orients the cartons 37A so that pick-up rods 77 will engage the V-shaped area between the carton cover and base.

FIG. 14 illustrates a plan view of the turret 100, on 75

each face of which are mounted the die assembly 102 (only one die assembly being shown). Under normal operating conditions, the cartons 37 are fed to the die assemblies 102 by the cross-feed conveyor 39. To properly understand the method of the feed and the safety features incorporated, it is important to understand that the cross-feed conveyor 39 is higher than the turret 100 and that the feed of the cartons 37 from the conveyor 39 to the die assemblies 102 is basically a gravity feed aided by the cam bar 106. An indication of the relative vertical levels of the conveyors 41, 42 and 39 with the turret 100 may be obtained from FIG. 1. In FIG. 1, the turret is strictly the item indicated as 100. All the structure mounted on top of the turret has to do with the electrical and hydraulic system described further on herein.

A safety feature is included in line with the cross-feed conveyor 39 to divert the flow of cartons 37 away from the turret 100. This diverting is automatically operated when the turret drive is stopped, which will prevent cartons from being left in the turret 100 when it has come to a stop. The diverting mechanism may also be manually operated by the machine operator when some major malfunction arises in connection with turret 100. As will be described further on, there are a number of other safety features which operate automatically when a carton 37 does not seat properly or when a carton is missing or if there arises a failure in the hydraulic pressure system. Accordingly, the diverting mechanism 104 needs to be employed only if a malfunction of greater moment, such as a breakdown in the drive to the turret 100, were to occur. A closeup front elevation view of the diverting mechanism 104 may be seen in FIG. 15 while its relationship to the cross-feed conveyor 39 and to the turret 100 may be seen in FIGS. 8, 9 and 16. The diverting mechanism 104 is located past the position where the pick-up arm 77 first engages the cartons 37.

The diverting mechanism 104 is composed of a section of track 105 and a cam bar 106 which are connected together by an arm 107. The arm 107 is pivotally mounted in the frame of the cross-feed conveyor 39 at pivot point 108. During normal operation, the track 105 is pivoted out of the way and the cam bar 106, which is curved in both the vertical and horizontal planes, serves to assure that the cartons 37 drop downwardly into the die assemblies 102 on the face of the turret 100. When the mechanism 104 is actuated by the operator, the cam bar 106 swings away from the path of the cartons 37 and the track section 105 swings into the path of the cartons 37 so as to provide a horizontal track on which the cartons 37 will travel. The track 105 is in a horizontal plane so as to prevent the cartons 37 from dropping down into the dies 102. Within that horizontal plane, the track 105 is curved (as may be seen in FIG. 7) so that the cartons can rotate under the impetus of the pick-up rods 77, which rods 77 carry the cartons 37 into a channel 109. Once in the channel 109, the cartons 37 contact a switch arm 110 that turns on an air blast to blow the cartons 37 clear of the rotary after press 40.

In FIG. 16 the diverting mechanism 104 can be seen in relationship to the curved track 78 on which the cartons 37 ride just before they leave the cross-feed conveyor 39 and to the channel 109 to which the cartons 37 are delivered when the diverting mechanism is swung into place. As shown in FIG. 16, the diverting mechanism 104 is in its retracted position, that is the horizontal section of track 105 is retracted and the cam bar 106 is in position to assure that the cartons 37 drop into the die assembly 91. FIG. 16 is a partial plan view and in viewing FIG. 16 it should be remembered that the track 78, the track section 105, and the channel 109 are in the same horizontal plane, whereas the cam bar 106 curves vertically. Thus the carton at position 37' is vertically located considerably above the carton when it has arrived at position 37".

FIG. 16 shows further details of the diverting mechanism 104. Thus FIG. 16 illustrates two mounting bars 112 on which the track section 105 is mounted and two channels 113 which guide the bars 112 as the track 105 is retracted or placed in position to divert cartons 37. Similarly two mounting bars 114 are shown for the cam bar 106. These mounting bars 114 are guided in channels 115 as the cam bar 106 pivots.

The function of the rotary after press 40 is to reform and finish, under heat and pressure, egg cartons presented to it by cross-feed conveyor 39. The turret 100 consists of an octagonal casting, the faces of which have attached to them die assemblies 102. On the top of turret 100 (see FIG. 1) and rotating thereon is the hydraulic assembly 118 which provides the necessary pressure for the die assemblies 102. On top of the hydraulic assembly 118 a conventional slip ring assembly in collector assembly 120 provides the necessary electric power. The cartons 37 pass around the turret 100 in a vertical plane.

As shown in FIGS. 1 and 14, the turret 100 is rotated by means of belt 122 which is in turn driven by the pulley 123 of vari-speed drive 124 which in turn is driven by motor 125. The vari-speed drive 124 utilizes the customary Reeves drive, whereby the use of hand wheel 126 permits a variable speed of rotation for the turret 100. FIG. 14 also shows a pulley 127 which is mounted on the vertical drive shaft 70 and which supplies power to the shaft 70 through belt 127a from the drive 124.

As may be seen in FIG. 17, the turret 100 is mounted on frame 128. The octagonal turret casting 129 is supported for free rotation by means of thrust bearings 130. A bull gear 131 driven by spur gear 132 provides the transfer of power from belt 122 to cause rotation of turret casting 129. Bull gear 131 is rigidly attached to turret casting 129 by means of bolts 134.

As has been described above, the pusher arms 66 carry the egg cartons 37 to the point at about which a horizontal center line of the rotary after press 40 is perpendicular to the longitudinal axis of the cross-feed conveyor 39. At that point pick-up rods 77 have engaged the V-shaped area between the bottom and the top of cartons 37. The roller 81 on pusher arm 66 contacts pusher closing cam 80 rotating arm 66 (counterclockwise in plan view as seen in FIG. 10) far enough so that the end of pusher arm 66 no longer engages the trailing edge of cartons 37. Pusher arm 66 is latched in the inoperative position by the movement of latching arm 76 which follows the movement of arm 66 until the shoulder 136 of pusher arm 66 enters notch 137 on the latching arm 76. The pusher arm 66 will remain in the retracted position until it is released by the tripping of the latching arm 76.

The cartons 37 now being propelled by the pick-up rods 77 are carried along the curved track 78 (see FIG. 16) to the point where the lower portion of track 78 ends. The cartons 37 no longer being supported drop by gravity into the space between inner die 139 and outer die 140 as shown in FIGS. 18 and 19. The cartons 37 come to rest against carton positioning ledge 141, which is pivotally attached to the fixed outer die 140, and halts the downward movement of the cartons 37, thereby placing the cartons in a vertical position ready for pressing by the die assembly 102. During the fall of carton 37 into position between dies 139 and 140, its movement is guided by creasing plates 142 (see FIGS. 18, 20 and 21). The creasing plates 142 hold the carton 37 upright and assure its proper orientation to the dies 139, 140.

The carton flap 37c must maintain its alignment with the rest of the carton 37 so that it will properly seat when the dies 139, 140 come together. A guide 143 is pivotally mounted on the movable inner die 139 to assure proper alignment of the flap 37c.

What happens in general, is that the cartons 37 drop

into the die assembly 102 so that they come to rest on the carton positioning ledge 141. The carton positioning ledge 141 has two switches 144, which are closed by the weight of the carton 37 (FIGS. 22 and 23 show this arrangement most clearly). The switches 144 actuate a solenoid (not shown) which connects the movable inner die 139 to a low pressure supply in the hydraulic system.

As die 139 closes a camming surface on the ledge 141 contacts the closing inner die 139 so that the die 139 causes the ledge 141 to pivot out of the way permitting the dies 139, 140 to continue to close. As may be seen in FIG. 24, a latching arm 145 engages the ledge 141 when the ledge 141 is thus pivoted and thereafter holds the ledge in the pivoted position until the end of the finishing cycle. As may be seen in FIGS. 18 and 19, the guide 143 for the flap 37c also pivots out of the way as the dies close because of the link 143a. The link 143a is pivotally mounted at one end to the outer die 140 and at the other end to an extension of the guide 143. As seen in FIG. 18, the guide 143 will pivot clockwise as the link 143a also pivots slightly clockwise when the dies 139, 140 close.

As the inner die 139 goes into contact with the outer die 140, a high pressure control switch 146 (see FIG. 20) is closed which actuates a solenoid (not shown) that introduces high pressure from the hydraulic system 118 to the inner die 139. Thus, low pressure is used to bring the dies 139, 140 together and high pressure is used, once the dies are together, to provide the pressure necessary to finish off the surface of the cartons 37.

The switches 144 on the ledge 141 act as a safety feature so that the absence of a carton 37, or the presence of a carton 37 so mis-aligned as not to hit the switches, will mean that no pressure from the hydraulic system will be delivered to the inner die 139 and thus the dies will not close without the presence of a properly positioned carton 37.

The operation of each inner and outer die assembly 102 is independent. Malfunction or the lack of a carton in proper position on positioning ledge 141 on a particular die assembly 102 does not prevent the operation of the remainder of the assemblies 102.

The creasing plates 142 are spring loaded so that they retract under pressure as the inner die 139 closes against the outer die 140. The flap 37c ledge 143 pivots out of the way along with the ledge 141.

Both inner die 139 and outer die 140 have fixed in them electric heating blocks 147 and 148 respectively (see FIG. 18). Heating blocks 147, 148 are thermostatically controlled in order to insure sufficient heat being supplied to the cartons 37 by conduction. The combined effect of heat and pressure during the rotation of the turret 100 effects the reforming or after finishing desired.

It will be appreciated that moisture may be supplied as necessary through openings in one or both of dies 139, 140 to further assist in this after forming operation.

The after finishing or reforming process takes place at about 240° of turret 100 rotation. Once the die assembly 102 has reached this amount of rotation a limit switch 149 on the rotating turret contacts die opening cam surface 150 mounted on the cross-feed conveyor frame 128 (see FIGS. 25, 26 and 27). Actuation of the limit switch 149 ends the high pressure cycle and starts the inner die 139 retracting. As the dies 139, 140 open, the cartons 37 are again held by creasing plates 142.

To assist the carton 37 in breaking away from dies 139, 140, an air blast is introduced through the face of either die 139 or 140 or both. The air blast is properly timed by the arrangement and design of a stationary plate 152, having port-holes 152A and 152B, as seen in FIGS. 17 and 17A. The plate 152 is located at the bottom of the turret 100 and is affixed to the turret frame 128. A portion of the rotating casting 129 is flush with the plate 152. Eight pairs of ports 153A, 153B are arranged in the portion of the casting 129 that is flush with the plate

152 so that as the casting 129 rotates, one pair of the casting ports 153A, 153B will line up with the plate ports 152A, 152B, respectively, at a time. The plate ports 152A and 152B communicate to elongated slots 154A and 154B, respectively, cut into the plate 152 so that there will be effective communication with the casting ports 153A and 153B for the adequate period of time. Air under pressure is continuously supplied to plate ports 152A and 152B. Each pair of casting ports 153A and 153B are connected by means of passageways to a separate face of the turret 100. Thus as the turret casting 129 rotates, a blast of air will be delivered in sequence to each of the turret faces. As long as the plate 152 is adjusted to the proper angular position, these blasts of air will be delivered at the right point in time during each cycle to blow the cartons 37 free of the dies 139, 140 after the cartons have been pressed and the dies 139, 140 have separated.

When the inner die 139 completes its return stroke, creasing plates 142 are open and the carton 37 is dropped onto a discharge conveyor which carries the after pressed or reformed cartons 37 onto subsequent operations such as perforating and printing.

After the carton 37 is dropped from the die assemblies 102, a cam 156 trips the latching arm 145 (see FIG. 24) and thus releases the ledge 141 which returns to a horizontal position. The creasing plates 142, being in their open position, the die assembly 102 is again in condition to receive a new carton.

FIG. 28 is a circuit diagram that illustrates the electrical connections which make possible the above described control over the dies 139, 140 as well as the safety features incorporated in the die operation.

The carton sensing switches 144, which are mounted on the stationary outer die 140, are two normally open spring return limit switches. These switches 144 are closed by the weight of a carton 37 when it is properly seated on the carton positioning ledge 141. A properly seated carton 37 will close the switches 144 and thereby energize the relay 160. The energized relay 160 will cause contacts 160a and 160c to close while opening contact 160b.

Further rotation of the turret 100 brings the die closing switch 161 into contact with the die closing cam 162, thereby closing the switch 161 and energizing the relay 163 through the closed switches 144 and closed contact 160a. The die closing switch 161 is a normally open spring return limit switch which is mounted on the outer die 140 and is closed through contact with the cam 162 which cam 162 is mounted on the cross-feed conveyor frame 128 (see FIGS. 26 and 27). The relay 163 upon being energized closes contacts 163a and 163c while opening contacts 163b and 163d. The closed contact 163c provides a holding circuit that maintains relay 163 energized after the die closing switch 161 has rotated past the cam 162 and thus re-opens.

The closing of contact 163a energizes the solenoid 164a. In turn the solenoid 164a switches an hydraulic valve into the "forward" position which thereby applies pressure from the low pressure hydraulic system to the inner die 139 in a direction to cause the inner die 139 to move and close against the outer die 140. It should be noted that the low pressure failure eject switch 165 will open as soon as the inner die 139 starts to move. The low pressure failure eject switch 165 is a normally open spring return limit switch that is mounted on the turret frame 128. The switch 165 is held closed only while the inner die 139 is at its maximum open position and thus the switch 165 opens as soon as the inner die 139 starts to move outward.

Further rotation of the turret 100 will cause the carton eject switch 166 to close. The carton eject switch 166 is a normally open spring return limit switch which is mounted on the outer stationary die 140. This switch is closed at the appropriate point in the turret 100

5 rotation by contact with a cam 167 mounted on the machine frame 128. Under normal operation, the opening of switch 165 followed by the closure of switch 166 has no effect.

10 Thus, under normal operation, the inner die 139 will continue to close as the turret 100 rotates. When the inner die 139 has completed about 90% of its excursion, it will contact the high pressure control switch 146, mounted on the outer die 140. The closing of terminal 146a of the high pressure control switch 146 energizes a solenoid 169 through the closed contact 163, which solenoid 169 switches a valve 216 in the high pressure hydraulic line to supply high pressure to the movable inner die 139 and thus exert the pressure on the carton 37 that is required for proper finishing.

15 As the turret 100 continues to rotate, the die opening switch 149 comes into contact with the cam 150 thereby causing relays 160 and 163 to become de-energized. The de-energization of relay 163 opens contact 163a and thereby de-energizes the solenoids 164a and 169 so that the valves in the low pressure hydraulic line and the high pressure hydraulic line are closed and all hydraulic pressure tending to press die 139 against die 140 is removed. In addition, the closing of contact 163b, as soon as the die opening switch 149 recloses as the turret 100 moves the switch 149 past the cam 150, causes the solenoid 164b to place hydraulic pressure from the low pressure line on the movable die 139 in a direction that causes the die 139 to retract from the die 140. The die opening switch 149 is a normally closed spring return limit switch which is mounted on the outer die 140. The switch 149 is opened at the appropriate point in the cycle by a cam 150 that is mounted on the turret frame 128. Thus, a complete normal cycle is completed.

20 The following description will indicate what occurs when either the carton fails to seat properly or one of the hydraulic pressure systems fails to operate properly.

25 If the carton 37 fails to seat properly, one or the other of the carton sense switches 144 will remain open and thus the relay 160 will not be energized. Because the contact 160a, therefore, remains open, the subsequent closing of the die closing switch 161 will not energize the relay 163 and thus no hydraulic pressure will be supplied to the inner die 139.

30 However, the carton eject switch 166, closed by the cam 167, will complete a circuit through the closed contact 163d to energize the solenoids 172, 173 and 174. All three solenoids 172, 173, 174 are mounted on the stationary outer die 140 and perform three separate functions to assure that the misaligned carton 37 is ejected. The solenoid 172, when energized, actuates the ledge 141 causing the ledge 141 to pivot out of the way. The solenoids 173 and 174, when energized, actuate the creasing plates 142 causing the plates 142 to be retracted. Thus the three solenoids remove mechanical support from the carton 37. A cam 180 (see FIGS. 18 and 29) is mounted at the rear of the die 140 in a manner such that it reciprocates with the creasing plates 142. When the plates 142 are retracted by the solenoids 173, 174, the cam 180 is extended and contacts the air ejection switch 181 (see FIGS. 26 and 27) mounted on the frame 128. The air ejection switch 181 is thereby closed and causes a blast of air to pass over the face of the dies to blow the now unsupported carton free of the die assembly 102.

35 If a low pressure failure is now assumed, the circuit (FIG. 28) will operate as follows. The normal seating of a carton 37 closes switches 144, energizing relay 160 and thus closing contact 160a. The subsequent closing of switch 161 should energize relay 163 and start the inner die 139 moving. However, if there is a failure in the low pressure system and the die 139 does not move, the low pressure eject switch 165 will remain closed. The subsequent closing of the carton eject

switch 166 will complete a circuit through switch 165 and the closed contacts 160c to energize the solenoids 172, 173, 174 and thus remove support from the cartons 37. The carton 37 is then ejected in the same fashion as above described in connection with the failure of a carton to seat properly.

Relay 175 is energized simultaneously with the solenoids 172, 173, and 174 therefore closing contacts 175b and opening contacts 175a. The opening of contact 175a opens the holding circuit to relay 163 thereby de-energizing relay 163 to assure that the die 139 does not close on the off chance that hydraulic pressure may become available past the closing of the carton eject switch 166. The contact 175b maintains relay 160 energized after the ledge 141 has swung away and thus opened the switches 144.

Assuming that the cycle operates properly except for a high pressure failure, then the following sequence will occur. The operation will be as described under the normal operating cycle above. However, when the switch 146 is closed as the dies come together, a high pressure sense switch 176 will react to the pressure in the high pressure line. As long as pressure is high the switch 176 will remain open. If the pressure drops below a certain level, the switch 176 will close and the relay 170 will become energized. The closing of contacts 170a and 170b will send a warning signal to start an audible alarm and turn on a warning pilot light. Contact 170c operates as a holding circuit to maintain relay 170 energized until the operator presses the reset button 177.

FIG. 29 illustrates the electrical controls for this invention including die control circuit discussed in detail in connection with FIG. 28. The circuits on the operator control panel are indicated within the broken line 185. The hydraulic motor 186 is controlled by stop and start buttons 187. A rectifier braking circuit 188 which brakes the motor that rotates the turret places D.C. current on the field windings of the motor to create a magnetic field which tends to brake the rotation of the rotor. This braking circuit is a standard commercial unit.

Also located in the operator control panel 185 are the dump conveyor 41, stop button 194, and start button 195. When the button 194 is depressed, the dump conveyor 41 will rotate to divert the cartons away from the cross-feed conveyor 139. Pressing the button 195 will return the dump conveyor to this normal operating position when desired.

When there is high pressure failure a signal produced because of the closing of the contacts associated with relay 170 is applied to the annunciator cabinet 200 which includes a horn 201 that provides an audible warning signal and an indicating light 202 which indicates which die assembly 102 has the high pressure failure.

The heating coils 205 associated with the inner die 139 are indicated in solid line. If desired coils 206 (indicated in dotted lines) may be supplied for the outer die.

FIG. 30 shows the arrangement of the ports and the valves of the hydraulic system when low pressure is being applied to the inner die 139 to open the dies. The solenoid 164b is energized to cause the ports in a pilot valve 210 to align as shown in FIG. 30. The pilot valve 210 ports then supply pressure to an hydraulically controlled main valve 212 to cause the valve 212 to align as shown in FIG. 30. When thus aligned, low pressure is fed to the rear of the piston 214 forcing the piston upward as seen in FIG. 30. The "up" position of the piston 214 represents the position of the die 139 when it is separated from the die 140. Concurrently the solenoid 169, not being energized, leaves the ports in the valve 216 removed from the high pressure line so that high pressure cannot be supplied to the piston 214.

In FIG. 31, all that has happened is that the solenoid 164a has become de-energized and the solenoid 164b has become energized, thereby switching the port arrange-

ment in the pilot valve 210 so that the main valve 212 has its port arrangement switched. Accordingly, low pressure is supplied to the face side of the piston 214 and the piston 214 is forced into the "down" position which represents a closed condition between the dies 139, 140. As illustrated in FIG. 31, the dies 139, 140 have not completely closed since the solenoid 169 has not yet been energized by the closure of the switch 146.

FIG. 33 represents the after pressing condition when the switch 146 has been closed by contact with the die 139 and thus has energized the solenoid 169. The energized solenoid 169 has switched the ports in the high pressure valve 216 so that high pressure is supplied to the piston 214 and thus exert high pressure between the face surfaces of the dies 139, 140.

The method and apparatus which have been described above provide for a substantial increase in the efficiency and reliability of an after-pressing operation. The system of this invention is versatile in that the speed of operation of all elements is synchronized and variable. By simple changes in dieblocks a wide variety of molded paper items can be given an after-pressing treatment. Built in safety features provide for continuous production in spite or normal operation in which less than six cartons are forwarded to the press 40, a carton is not properly seated or in condition arising out of a failure in one or more of the elements in the die assembly to operate properly.

The automatic features, speed, reliability and versatility of the method and device of this invention results in an improvement in production in both quality and quantity.

While a preferred embodiment and certain modifications have been described in detail it should be understood that changes will occur to others which are within the spirit of the claims below.

What is claimed is:

1. An automatic continuous flow finishing machine for molded pulp paper articles comprising
  - a rotatable turret for carrying said paper articles through the finishing stage,
  - pressure means mounted on said turret for applying pressure to said paper articles while being carried on said turret, and
  - positioning means on the turret in addition to the pressure means to position said paper articles on said turret temporarily until said pressure means engages said articles and in such a fashion as to permit said pressure means to properly engage said paper articles.
2. An automatic continuous flow finishing machine for molded pulp paper articles comprising
  - a rotatable turret for carrying said paper articles through the finishing stage,
  - pressure means mounted on said turret for applying pressure to said paper articles while being carried on said turret, said pressure means including a pair of dies for engaging said articles while pressure is applied through said dies, and
  - positioning means on the turret to position said paper articles on said turret temporarily until said dies engage said articles and in such a fashion as to permit said dies to properly engage said paper articles.
3. An automatic continuous flow finishing machine for molded pulp paper articles comprising
  - a rotatable turret for carrying said paper articles through the finishing stage,
  - pressure means mounted on said turret for applying pressure to said paper articles while being carried on said turret, and
  - positioning means to position said paper articles on said turret in such a fashion as to permit said pressure means to properly engage said paper articles, said positioning means including a retractable ledge mounted on said turret for temporarily supporting

said articles and a retractable spring loaded pressure plate for holding said articles upright against a portion of said pressure means.

4. An automatic continuous flow finishing machine for molded pulp paper articles comprising

a rotatable turret having a plurality of vertically disposed faces,

an inner die mounted on a first one of said turret faces, an outer die mounted on said first one of said turret faces,

positioning means to position said paper articles between said inner die and said outer die in such a fashion as to permit said dies to properly engage said paper articles when said dies are closed, and

pressure means connected to said dies including a low pressure means for closing said dies and a high pressure means connectable to said dies when said dies are closed by said low pressure means.

5. An automatic continuous flow finishing machine for molded pulp paper articles comprising

a rotatable turret having a plurality of vertically disposed faces,

an inner die mounted on a first one of said turret faces, an outer die mounted on said first one of said turret faces,

positioning means to position said paper articles between said inner die and said outer die in such a fashion as to permit said dies to properly engage said paper articles when said dies are closed, said positioning means including a pivotable ledge mounted on said turret for temporarily supporting said articles, said ledge being cammed to pivot out of the way as said dies close,

pressure means connected to said dies including a low pressure hydraulic source for closing said dies and a high pressure hydraulic source connectable to said dies when said dies are closed by said low pressure source.

6. An automatic continuous flow finishing machine for molded pulp paper articles comprising

a rotatable turret having a plurality of vertically disposed faces,

an inner die mounted on a first one of said turret faces, an outer die mounted on said first one of said turret faces,

positioning means to position said paper articles between said inner die and said outer die in such a fashion as to permit said dies to properly engage said paper articles when said dies are closed,

pressure means connected to said dies comprising a low pressure means for closing said dies and a high pressure means connectable to said dies when said dies are closed by said low pressure source,

safety means responsive to the orientation of said articles to said dies and connected to said positioning means to withdraw said positioning means when said articles are improperly oriented and to actuate an air blast to blow said improperly oriented articles free of said dies,

said safety including means responsive to the closing motion of said dies and connected to said positioning means to withdraw said positioning means when said dies fail to close after a certain point in the operating cycle and to actuate an air blast to blow whatever articles may be between said dies free of said dies.

7. An automatic continuous flow finishing machine for molded pulp paper articles comprising

a rotatable turret having a plurality of vertically disposed faces,

an inner die mounted on a first one of said turret faces, an outer die mounted on said first one of said turret faces to face said inner die,

positioning means to position said paper articles between said inner die and said outer die in such a fashion as to permit said dies to properly engage said

paper articles when said dies are closed, said positioning means including a pivotable ledge mounted on said turret for temporarily supporting said articles, said ledge being cammed to pivot out of the way as said dies close, said positioning means also including a retractable spring loaded pressure plate to hold said articles against one of said dies when said dies are apart,

pressure means connected to said dies comprising a low pressure hydraulic source for closing said dies and a high pressure hydraulic source connectable to said dies when said dies are closed by said low pressure source,

safety means responsive to the orientation of said articles to said dies and connected to said positioning means to withdraw said positioning means when said articles are improperly oriented and to actuate an air blast to blow said improperly oriented articles free of said dies,

said safety means including means responsive to the closing motion of said dies and connected to said positioning means to withdraw said positioning means when said dies fail to close after a certain point in the operating cycle and to actuate an air blast to blow whatever articles may be between said dies free of said dies.

8. An automatic continuous flow finishing machine for molded pulp paper articles comprising

a rotatable turret having a plurality of vertically disposed faces, each of said faces adapted to hold at least one of said articles for carrying said articles through the finishing stage,

power means coupled to said turret for continuously rotating said turret,

pressure means, including an inner and an outer die mounted on a first one of said turret faces for applying pressure to said articles during said finishing stage,

positioning means for positioning said articles between said inner die and said outer die prior to said finishing stage so that said dies will properly mesh with said articles when supplying pressure to said articles during said finishing stage,

safety means responsive to the orientation of said articles to said dies and connected to said positioning means to withdraw said positioning means when said articles are improperly oriented and to actuate an air blast to blow said improperly oriented articles free of said dies,

said safety means including means responsive to the closing motion of said dies and connected to said positioning means to withdraw said positioning means when said dies fail to close after a certain point in the operating cycle and to actuate an air blast to blow whatever articles may be between said dies free of said dies.

9. An automatic continuous flow finishing machine for molded pulp paper articles comprising

a rotatable turret for carrying said articles through the finishing stage of compression and heating,

power means coupled to said turret for continuously rotating said turret,

conveyor means synchronized with said turret for conveying and feeding said articles to said turret at a rate compatible with the rate at which said turret carries said articles through said finishing stage,

pressure means, including a pair of dies mounted on said turret, for supplying pressure to said articles during said finishing stage,

positioning means for positioning said articles between each one of said pair of dies prior to said finishing stage so that said dies will properly mesh with said articles when supplying pressure to said articles during said finishing stage, and

control means connected to said dies and to said posi-

tioning means to assure the proper sequence of die closing, removal of said positioning means from interference with said die closing, application of pressure, and die opening during said finishing stage.

10. An automatic continuous flow finishing machine for molded pulp paper articles comprising

a turret having a plurality of vertically disposed faces, each of said faces adapted to hold at least one of said articles,

power means coupled to said turret for continuously rotating said turret,

a fixed inwardly facing outer die mounted on one of said faces of said turret,

a reciprocable outwardly facing inner die mounted on said one of said faces of said turret and facing said inner die,

conveyor means synchronized with said turret to feed an article between said inner die and said outer die, a pivotable ledge mounted on one of said dies to hold said article against the force of gravity, said ledge being cammed to pivot out of the way when said inner die closes on said outer die,

a retractable spring loaded pressure plate projecting from the face of one of said dies to hold said article flush against the face of the other one of said dies,

pressure means connected to said dies comprising a low pressure hydraulic source for closing said dies and a high pressure hydraulic source connectable to said dies when said dies are closed by said low pressure source,

safety means responsive to the orientation of said article to said dies and connected to said ledge and to said retractable plate to pivot said ledge and retract said plate when said article is improperly oriented and to actuate an air blast to blow said improperly oriented article free of said dies, and

said safety means including means responsive to the closing motion of said dies and connected to said ledge and to said retractable plate to pivot said ledge and retract said plate when said dies fail to close after a certain point in the operating cycle and to actuate an air blast to blow whatever article may be between said dies free of said dies.

11. An automatic continuous flow finishing machine for molded pulp paper egg cartons comprising

a turret having a plurality of vertically disposed faces, each of said faces adapted to hold at least one of said cartons, for carrying said cartons through the finishing stage,

power means coupled to said turret for continuously rotating said turret,

pressure means, including an inner die and an outer die mounted on a first one of said turret faces, for applying pressure to said cartons during said finishing stage, conveyor means for conveying a carton to said turret, a vertical rod connected to and rotating with said first turret face to guide a carton from the output end of said conveyor means to a properly oriented position between said inner dies and said outer die,

a horizontal ledge pivotally connected to one of said dies to hold said carton at a proper height between said dies,

a retractable creasing plate protruding from the face of one of said dies to engage the edges of said carton and hold said carton flush against the face of the other one of said dies,

means for pivoting said ledge and retracting said creasing plate as said dies move together under the impetus of said pressure means,

safety means responsive to the orientation of said articles to said dies and connected to said ledge and to said creasing plate to pivot said ledge and retract said plate when said article is improperly oriented and to actuate an air blast to blow said improperly oriented article free of said dies, and

said safety means including means responsive to the closing motion of said dies and connected to said ledge and to said creasing plate to pivot said ledge and retract said plate when said dies fail to close after a certain point in the operating cycle and to actuate an air blast to blow whatever article may be between said dies free of said dies.

12. An automatic continuous flow finishing machine for molded pulp paper items comprising

an infeed conveyor to receive and align said items, said conveyor having a plurality of channels so as to provide a series of aligned sets of said items,

a cross-feed conveyor having its input end adjacent to the output end of said infeed conveyor, said cross-feed conveyor adapted to receive a single one of said sets of said items at a time, feeding means in said cross-feed conveyor to move said items along said cross-feed conveyor to the output end of said cross-feed conveyor,

a multi-faced rotatable turret adjacent to said output end of said cross-feed conveyor for receiving and finishing said items,

positioning means for properly placing each of said items on a separate one of said faces as said items come off said cross-feed conveyor, and

pressure means mounted on said turret for applying pressure to said items while being carried on said turret.

13. An automatic continuous flow finishing machine for molded pulp paper articles comprising

a rotatable turret having a plurality of vertically disposed faces, each of said faces being adapted to hold at least one of said articles,

power means coupled to said turret for continuously rotating said turret,

conveyor means synchronized with said turret for conveying and feeding said articles to said turret faces at a rate compatible with the rate of which said turret carries said articles through said finishing stage,

safety means comprising a rotatable portion of said conveyor means for diverting said articles from said turret, and

said safety means further comprising a movable track section adapted to be moved to a position adjacent to the output end of said conveyor means, thereby to divert said articles from said turret, said safety means including an air blast outlet actuated by a diverted article to blow said diverted article away from said rotating turret.

14. An automatic continuous flow finishing machine for molded pulp paper egg cartons comprising

a rotatable turret having a plurality of vertically disposed faces, each of said faces being adapted to hold at least one of said cartons,

power means coupled to said turret for continuously rotating said turret,

conveyor means synchronized with said turret for conveying and feeding said cartons to said turret faces at a rate compatible with the rate at which said turret carries said cartons through said finishing stage,

safety means comprising a rotatable portion of said conveyor means for diverting said cartons from said turret,

said safety means further comprising a movable track section adapted to be moved to a position adjacent to the output end of said conveyor means, thereby to divert said cartons from said turret, said safety means including an air blast outlet actuated by a diverted carton to blow said diverted carton away from said rotating turret, and

a vertical rod connected to and rotating with said turret to guide cartons from the output end of said conveyor means to a properly oriented position on said turret faces.

15. An automatic continuous flow finishing machine for molded pulp paper articles comprising
 a rotatable turret for carrying said articles through the finishing stage,
 power means coupled to said turret to rotate said turret,
 conveyor means synchronized with said turret for conveying and feeding said articles to said turret at a rate compatible with the rate at which said turret carries said articles through said finishing stage,
 a dumping conveyor portion of said conveyor means, said dumping conveyor constituting said input end of said conveyor means,
 a timing and aligning conveyor portion of said conveyor means, said timing and aligning conveyor having its input end adjacent to the output end of said dumping conveyor and adapted to move said articles at a faster speed than said dumping conveyor thereby avoiding a pile up of said articles at the output end of said timing and spacing conveyor, safety means connected to said dumping conveyor for rotating the frame of said dumping conveyor so that the position of the output end of said dumping conveyor is removed from the input end of said timing and aligning conveyor while the position of the input end of said dumping conveyor is not substantially moved, whereby an operator may divert the flow of articles from the remainder of said conveyor means,
 a cross-feed conveyor portion of said conveyor means having its input end adjacent to the output end of said timing and aligning conveyor to feed said articles to said turret.

16. An automatic continuous flow finishing machine for molded pulp paper articles comprising
 a rotatable turret having a plurality of vertically disposed faces for carrying said articles through the finishing stage,
 power means coupled to said turret to rotate said turret,
 conveyor means synchronized with said turret for conveying and feeding said articles to said turret faces at a rate compatible with the rate at which said turret carries said articles through said finishing stage,
 a dumping conveyor portion of said conveyor means, said dumping conveyor constituting said input end of said conveyor means,
 a timing and aligning conveyor portion of said conveyor means, said timing and aligning conveyor having its input end adjacent to the output end of said dumping conveyor and adapted to move said articles at a faster speed than said dumping conveyor thereby avoiding a pile up of said articles at the output end of said timing and spacing conveyor, safety means connected to said dumping conveyor for rotating the frame of said dumping conveyor so that the position of the output end of said dumping conveyor is removed from the input end of said timing and aligning conveyor while the position of the input end of said dumping conveyor is not substantially moved, whereby an operator may divert the flow of articles from the remainder of said conveyor means,
 a cross-feed conveyor portion of said conveyor means having its input end adjacent to the output end of said timing and aligning conveyor to feed said articles to said turret, and
 positioning means near the output end of said cross-feed conveyor to proper position said articles on said turret, and
 said safety means further comprising a movable track section adapted to be moved to a position adjacent to the output end of said cross-feed conveyor, thereby diverting said articles from said turret, said second safety means including an air blast outlet ac-

tuated by a diverted article to blow said diverted article away from said rotating turret.

17. The finishing machine of claim 16 wherein said timing and aligning conveyor has its output end at a higher level than the input end of said cross-feed conveyor and wherein said cross-feed conveyor has its output end at a higher level than said faces, thereby effecting a gravity feed of said articles from said timing and aligning conveyor to said cross-feed conveyor and from said cross-feed conveyor to said turret faces.

18. An automatic continuous flow finishing machine for molded pulp paper articles comprising
 a rotatable turret having a plurality of vertically disposed faces for carrying said articles through the finishing stage,
 conveyor means synchronized with said turret for conveying and feeding said articles to said turret faces at a rate compatible with the rate at which said turret carries said articles through said finishing stage, safety means connected to said conveyor means to rotate a portion of the frame of said conveyor means to divert the flow of articles from said turret, said safety means further comprising a movable track section adapted to be moved to a position adjacent to the output end of said conveyor means, thereby diverting said articles from said turret, said safety means including an air blast outlet actuated by a diverted article to blow said diverted article away from said turret,

pressure means, including an inner die and an outer die mounted on a first one of said turret faces for applying pressure to said articles during said finishing stage, positioning means for positioning said articles between said inner die and said outer die prior to said finishing stage so that said dies will properly mesh with said articles when supplying pressure to said articles during said finishing stage, said safety means further including means responsive to the orientation of said articles to said dies and connected to said positioning means to withdraw said positioning means when said articles are improperly oriented and to actuate an air blast to blow said improperly oriented articles free of said dies, and said safety means further including means responsive to the closing motion of said dies and connected to said positioning means to withdraw said positioning means when said dies fail to close after a certain point in the operating cycle and to actuate an air blast to blow whatever articles may be between said dies free of said dies.

19. An automatic continuous flow finishing machine for molded pulp paper articles comprising
 a rotatable turret having a plurality of vertically disposed faces,
 an inner die mounted on a first one of said turret faces, an outer die mounted on said first one of said turret faces, positioning means to position said paper articles between said inner die and said outer die in such a fashion as to permit said dies to properly engage said paper articles when said dies are closed, and pressure means connected to said dies for closing said dies and exerting pressing forces on said paper articles.

20. An automatic continuous flow finishing machine for molded pulp paper articles comprising
 a rotatable turret having a plurality of vertically disposed faces,
 an inner die mounted on a first one of said turret faces, an outer die mounted on said first one of said turret faces, positioning means to position said paper articles between said inner die and said outer die in such a fashion as to permit said dies to properly engage said paper articles when said dies are closed, and

21

feed means connected to supply said paper articles to said positioning means in timed synchronization with rotation of said rotatable turret.

21. An automatic continuous flow finishing machine for molded pulp paper articles comprising
a rotatable turret having a plurality of vertically dis-

5

posed faces,
an inner die mounted on a first one of said turret faces,

an outer die mounted on said first one of said turret

faces,

positioning means to position said paper articles be-
tween said inner die and said outer die in such a
fashion as to permit said dies to properly engage
said paper articles when said dies are closed, and

10

22

feed means connected to supply said paper articles to said positioning means in timed synchronization with rotation of said rotatable turret, said feed means further including mechanisms for permitting said paper articles to be fed to said positioning means under the influence of gravity.

UNITED STATES PATENT OFFICE
CERTIFICATE OF CORRECTION

Patent No. 3,142,613

July 28, 1964

Kenneth L. Crabtree et al.

It is hereby certified that error appears in the above numbered patent requiring correction and that the said Letters Patent should read as corrected below.

Column 6, line 18, for "49" read -- 59 --; line 49, for "ends" read -- end --; line 51, for "sides" read -- side --; column 12, line 11, for "163" read -- 163a --; column 14, line 24, for "les" read -- less --; column 15, line 60, after "safety" insert -- means --.

Signed and sealed this 8th day of December 1964.
